SULPHONIC ACIDS AND PROCESS OF
PREPARING THEMLudwig Orthner and Werner Langbein, Frank-
fort-on-the-Main, Germany; vested in the
Alien Property CustodianNo Drawing. Application August 3, 1940, Serial
No. 351,153. In Germany July 13, 1939

5 Claims. (Cl. 260—513)

The present invention relates to sulphonic acids and to a process of preparing them. It is an object of the invention to prepare sulphonic acids from beta-halogenether compounds and alkali sulphites, the new compounds having capillary active properties and being suitable as adjuvants in the textile industry, for instance as wetting, dispersing and washing agents.

We have found that sulphonic acids are obtained by reacting alkali sulphites with beta-halogen-ethers prepared by condensing alkylene oxides with a member of the group consisting of halogen-methyl-ethers derived from aliphatic and carbocyclic compounds containing an aliphatic radical with at least four carbon atoms and further containing at least one hydroxyl group, and halogenmethylamides derived from aliphatic and carbocyclic carboxylic and sulphonnic acids containing an aliphatic radical with at least four carbon atoms. The products obtained may be designated by the following general formula

wherein R stands for a member of the group consisting of aliphatic and carbocyclic radicals containing an aliphatic radical with at least four carbon atoms, and X stands for a member of the group consisting of oxygen, carboxylic acid amide and sulphonnic acid amide.

As aliphatic or carbocyclic compounds containing at least one aliphatic radical with four carbon atoms and further containing at least one alcoholic hydroxyl group, there may be named, for instance: butanol, n-octylalcohol, alpha-ethylhexylalcohol, dodecyclalcohol, oleyl-alcohol, p-butyl-cyclohexanol, octodecandiol. It is not necessary to start from proper alcohols, but there may also be used commercial mixtures, as they are obtained in the hydrogenation of fats and oils, in the synthesis of methanol or in the hydrogenation of the products obtained by the oxidation of paraffine, for instance the alcoholic mixtures obtained by the hydrogenation of palm oil or coconut oil. The carbon skeleton of the compounds containing at least one alcoholic hydroxyl group may be interrupted by hetero atoms or hetero atom groups. As such compounds there may be named, for instance: iso-octylphenylmonoglycolether and p-dodecyl-N-dihydroxyethylaniline.

The halogenmethyl-ethers may be obtained in the usual manner from the compounds named, for instance by the action of formaldehyde and

hydrochloric acid, if necessary in the presence of an indifferent solvent or diluent.

In order to obtain halogenmethyl-amides, there may be used as starting materials the amides of the following acids: butyric acid, caproic acid, caprylic acid, lauric acid, palmitic acid, stearic acid, oleic acid, linolic acid, further the amides of the carboxylic acids obtained by the saponification of whale oil or by the oxidation of paraffines. Moreover there may be used sulphamides, especially those obtained by the simultaneous action of sulphur dioxide and chlorine upon paraffine hydrocarbons and the subsequent reaction with ammonia. Moreover there are suitable for the process of the present invention the amides from alkylated aromatic, hydroaromatic or araliphatic carboxylic or sulphonnic acids.

From the amides the halogenmethyl-amides may be obtained, for instance by the action of formaldehyde and hydrochloric acid, if necessary in the presence of an indifferent solvent or diluent.

The beta-halogenethers obtainable by reacting the halogen-methyl-ethers or -amides with a suitable alpha, beta-alkylenoxide, for instance ethylene oxide, propylene oxide, butylene dioxide, glycide, if necessary at a raised temperature and under pressure, are transformed into ether sulphonnic acids by the action of alkali sulphite, for instance by heating them to about 160—170° C. in an aqueous or aqueous-alcoholic solution.

The process of the present invention makes use of easily obtainable alcohols or alcoholic mixtures or of amides or mixtures of amides, products with valuable capillary active properties being obtained in a simple manner. The ether-sulphonnic acids so obtained constitute in the form of their salts in some cases viscous masses, in other cases white to yellowish, water-soluble powders. The products have an excellent stability towards the agents which cause the hardness of water and a good wetting, foaming, emulsifying and washing power. Some of the products may also be used as leveling, through-dyeing and softening agents. As washing agents the products serve for cleansing household articles and textile materials, especially wool, cotton, silk, artificial silk, as well as for hygienic purposes.

The products may be used either alone or in admixture with each other or with other capillary active substances, such as soap and other adjuvants of the textile industry, with colloidal substances, as for instance mucilage, glue, water-

soluble cellulose derivatives, starch, bentonite, saponine or the like, as well as in admixture with inorganic salts, for instance Glauber's salt, sodium carbonate, sodium pyrophosphate, sodium metaphosphate, tri-sodium-phosphate or with organic salts having complex forming properties, as for instance the salts of nitrilo-tri-acetic acid or of ethylene bis-iminodiacetic acid, with agents yielding oxygen, such as sodium perborate, or with sodium hypochlorite.

The following examples serve to illustrate the invention, but they are not intended to limit it thereto, the parts being by weight.

(1) 130 parts of octylalcohol are dissolved in twice the quantity of methylene chloride. 45 parts of paraformaldehyde are then added, hydrochloric acid gas being introduced at 0° C.-5° C., while stirring, until the solution is saturated. After the separation of the aqueous layer the product is dried by means of calcium chloride and filtered, whereupon the methylene chloride is separated by distillation. The octylchloromethylether obtained is then distilled under reduced pressure.

178.5 parts of octylchloromethylether are heated with 60 parts of ethylene oxide for 6 hours in a closed vessel at 160° C. to 170° C. The ethylene oxide in excess is then separated. By the absorption of 1 mol. of ethylene oxide the octylmethyl-ether-beta-chloroethylether has been formed.

222.5 parts of the above ether are heated for 10 hours, while stirring, at 150-160° C. with a solution of 170 parts of sodium sulphite in 400 parts of water and 800 parts of methanol. After cooling the product is filtered with suction and recrystallized from methanol.

(2) 234.5 parts of dodecyl-chloromethyl-ether are heated for 6 hours at 160-170° C. with 60 parts of ethylene oxide, the solution being worked up in the manner indicated in Example 1. 278.5 parts of the dodecyl-methylether-beta-chloroethylether obtained having the formula $C_{12}H_{25}-O-CH_2-O-CH_2-CH_2-Cl$ are heated for 10 hours at 150-160° C. with a solution of 210 parts of potassium sulphite in 400 parts of water and 800 parts of methanol. After cooling the product is filtered with suction and recrystallized from methanol.

(3) 360.5 parts of oleylchloromethylether are heated for 6 hours at 160-170° C. with 60 parts of ethylene oxide. 316.5 parts of the oleyl-methylether-beta-chloroethylether obtained are heated for 10 hours, while stirring, at 150-160° C. with a solution of 170 parts of sodium sulphite in 400 parts of water and 800 parts of methanol. The product is redissolved from methanol.

(4) 262.5 parts of the chloromethylether from the mixture of alcohols obtainable by the reduction of palm oil, are heated for 6 hours at 160-170° C. with 60 parts of ethylene oxide. 306.5 parts of the beta-chloroethylether obtained are heated for 10 hours, while stirring, at 150-160° C. with a solution of 170 parts of sodium sulphite in 400 parts of water and 800 parts of methanol. The product obtained may be redissolved from methanol.

(5) 178.5 parts of the chloromethylether derived from a mixture of alcohols containing 7 to 9 carbon atoms, obtainable by the oxidation of paraffine, are heated for 6 hours at 160-170° C. with 60 parts of ethylene oxide. 222.5 parts of the beta-chloroethylether obtained are heated for 10 hours, while stirring, at 150-160° C. with a solution of 170 parts of sodium sulphite in 400

parts of water and 800 parts of methanol. The product obtained may be redissolved from methanol.

(6) 250 parts of octylphenylmonoglycolether are dissolved in twice the quantity of methylene chloride. 45 parts of para-formaldehyde are then added and hydrochloric acid gas is introduced at 0-5° C., while stirring, until the solution is saturated. After the separation of the aqueous layer, the solution is dried by means of calcium chloride. After filtering, the methylene chloride is separated by distillation. 298.5 parts of octylphenyl monoglycoletherchloromethylether are heated for 6 hours at 160-170° C. with 60 parts of ethylene oxide. 342.5 parts of the octylphenyl-monoglycolether - methylether-beta-chloroethylether obtained are heated for 10 hours, while stirring, at 150-160° C. with a solution of 170 parts of sodium sulphite in 400 parts of water and 800 parts of methanol. The product obtained is purified by redissolving it from methanol.

(7) 375.5 parts of stearic acid beta-chloroethoxymethylamide are heated for 10 hours, while stirring, at 150-160° C. with a solution of 170 parts of sodium sulphite in 400 parts of water and 800 parts of methanol. After cooling, the sodium salt of the sulphonate acid having the formula

$C_{18}H_{37}-CO-NH-CH_2-O-CH_2-CH_2SO_3H$ is filtered with suction and recrystallized from methanol. Instead of sodium sulphite there may be used potassium sulphite. The initial material is obtained as follows:

283 parts of stearic acid amide are dissolved in twice the quantity of methylene chloride. 45 parts of paraformaldehyde and 90 parts of pulverulent calcium chloride are then added, hydrochloric acid gas being introduced at 0° C.-5° C., while stirring, until the solution is saturated. The solution is filtered with suction and rapidly dried by means of further calcium chloride. After filtering the methylene chloride is separated by distillation; the stearic acid chloromethylamide remains in form of a fatty mass.

331.5 parts of stearic acid chloromethylamide are heated for 6 hours at 160-170° C. in a closed vessel with 60 parts of ethylene oxide, whereupon the ethylene oxide in excess is separated. With absorption of 1 mol of ethylene oxide the stearic acid beta-chloroethoxymethylamide has been formed.

(8) 370.5 parts of a sulphonate acid beta-chloroethoxymethylamide obtainable in the manner described below, are heated for 10 hours at 150-160° C. with a solution of 210 parts of potassium sulphite in 400 parts of water and 800 parts of methanol. After cooling, the product is filtered with suction and redissolved from methanol.

The initial material is obtained as follows:

By treating paraffine hydrocarbons having a boiling point of 220-320° C., with equimolecular amounts of sulphur dioxide and chlorine, a mixture of aliphatic sulphochlorides is obtained. By reacting this mixture with ammonia, a mixture of aliphatic sulphamides having an average carbon chain of 14 atoms is obtained. By proceeding in the manner indicated in Example 7, a mixture of aliphatic sulphochloromethylamides is finally obtained.

326.5 parts of this mixture are heated for 6 hours at 160-170° C. with 60 parts of ethylene oxide, the product being worked up as indicated in Example 7.

(9) 312 parts of dodecylcyclohexylmonoglycol-

ether are transformed into the chloromethylether by the action of 45 parts of paraformaldehyde and hydrochloric acid. By reacting this chloromethylether with ethylene oxide, the dodecylcyclohexylmonoglycoether - methylether - beta - chloroethylether is obtained, which is then transformed into the corresponding sulphonate by means of sodium sulphite in an aqueous methanol solution. The sulphonate obtained may be redissolved from methanol.

(10) 263 parts of octylphenoxyacetic acid amide are dissolved in twice the amount of methylene chloride. 45 parts of paraformaldehyde and 90 parts of anhydrous sodium sulphate are then added, hydrochloric acid gas being introduced at 0° C.-5° C., until the solution is saturated. After filtering, the methylene chloride is separated by distillation.

311.5 parts of the octylphenoxyacetic acid chloromethylamide are heated at 160-170° C. with 60 parts of ethylene oxide, whereupon the ethylene oxide in excess is separated.

355.5 parts of the octylphenoxyacetic acid beta-chloroethoxymethylamide are heated for 10 hours at 150-160° C., while stirring, with 170 parts of sodium sulphite in 400 parts of water and 800 parts of methanol. After cooling, the product is filtered with suction and recrystallized from methanol.

We claim:

1. The process which comprises reacting a halogenmethyl-ether of an aliphatic compound containing an aliphatic radical of at least 4 carbon atoms and at least 1 hydroxyl group with an alkyleneoxide and reacting the resulting compound with an alkali sulphite.
2. The process which comprises reacting chloromethyl-ether of dodecyl alcohol with ethylene oxide and reacting the resulting beta-chlor-ethyl-ether with an alkali sulphite to replace the beta-chlor group by a sulphonic acid group.
3. The process as defined in claim 1 wherein the reaction with the alkali sulphite is effected at a temperature ranging from 160 to 170° C.
4. As new compounds the sulphonic acids of the general formula

20 wherein R stands for an aliphatic radical with at least four carbon atoms, and X stands for oxygen.

5. The compound of the formula

LUDWIG ORTHNER.
WERNER LANGBEIN.
